UNITED STATES PATENT OFFICE

2,078,894

DIRECTION SIGNAL

John Ralph Haines, Medford, N. J., assignor to
 Arrow Safety Device Company, Inc., Mount
 Holly, N. J., a corporation of New Jersey

Refiled for abandoned application Serial No.
 591,247, February 5, 1932. This application
 April 2, 1936, Serial No. 72,320

3 Claims. (CL 177—329)

This patent matures from the refiled application on the invention subject matter disclosed in an application 591,247, filed February 5, 1932, which has been abandoned.

5 The object of the invention is to provide a direction signal in which the elements necessary to give it the compartmental form required in such a device are cover carried, so that when the cover is removed, free access will be had to all 10 parts of the housing and the illuminating elements carried therein; to provide a direction signal in which reflectors are employed for the indicating lights and perform the additional function of the division walls of the compartment; and generally to provide a direction signal which is of simple form, susceptible of cheap manufacture and of a character to reduce to a minimum the liability to disarrangement of its parts.

20 With this object in view, the invention consists in a construction and combination of parts, of which a preferred embodiment is illustrated in the accompanying drawings, in which:

Figure 1 is a perspective view of the invention.
 25 Figure 2 is a sectional view on the plane indicated by the line 2—2 of Figure 1.

Figures 3 and 4 are sectional views on the planes indicated by the lines 3—3 and 4—4 respectively of Figure 2.

30 Figure 5 is a perspective view of the combined compartmental and reflector units.

Figure 6 is a perspective view of the cover unit.

The improved signal or indicator comprises a 35 housing 1 generally of diamond shape in elevation and drawn from sheet metal so that the top, bottom, and walls and back blend into each other. The open face of the casing is closed by a cover unit 2 which is formed by the marginal 40 flange 3 telescoping over the inset or rabbeted marginal portions of the walls of the casing 1.

The cover unit is punched to provide an opening 5, which defines the arrow head 6 at one side and a similar arrow head 7 at the other, the two 45 being connected by a stem portion 8. A transparency, preferably glass, is carried against the inner face of the cover unit within the flange 3 thereof, this transparency being extended to cover the openings 11 and 12 which are formed 50 in the cover member in the areas between the arrow heads 6 and 7 and above and below the stem portion 8 respectively.

The several light units are mounted in the casing respectively behind the arrow heads 6 and 7 and the openings 11 and 12, and to this end

there is provided a plate 13 formed with upwardly and downwardly extending arms as well as laterally extending arms. The upwardly and downwardly extending arms 15 and 16 respectively carry the sockets 17 and 18 designed for the reception of the bases of the lamps 19 and 20, which are retained in the sockets by the conventional pin and bayonet slot connections 21. The plate 13 is centrally depressed and in this depressed portion is secured to the back wall 10 of the housing 1 as indicated at 13a. A block of insulation 23 is seated in the depressed portion of the plate, and to it are secured by means of the fasteners 22a and 22b the contacts 22, which are in the form of spring strips whose 15 extremities bear on the center contacts of the lamps.

The lateral arms 24 and 25 of the plate 13 also carry lamp sockets. These lamp sockets 26 and 27 receive the lamps 28 and 29 which function to 20 respectively illuminate the arrow heads 6 and 7. The bases of the lamps 28 and 29 are provided with the pins 30 engaging the bayonet slots in the sockets, and the center contacts of the latter are engaged with the extremities of the 25 spring contacts 31 and 32 which are mounted on the block 23 by means of screws 31a and 31b and 32a and 32b respectively. This arrangement provides a ground connection for all of the several sockets, so that a common return to 30 the sources of current is provided. That the lamps may be selectively lighted, each of the spring contacts is connected with a suitable lead, and several leads or conductors 34 being brought into the casing through an opening 35 in the 35 rear wall thereof, which opening is continued through the insulating block 23.

The division of the casing into compartments is accomplished by the use of combined reflector and partition member 37, which is in one piece, 40 being punched from sheet metal and thereafter drawn into the conformation shown so that a reflecting surface 40 is provided of parabolic curvature adjacent the axis of the reflector which is coincident with the center of the opening 41, which is a clearance opening for its attendant lamp. The combined reflector and partition member 37 is provided with lateral portions 42 and 43 contacting at the edge 44, the space above the extensions defining the compartment back of the opening 11 in the cover unit and the space below defining the compartment behind the opening 12 of the cover unit. The remote ends 45 of the unit 37 follow the contour of the remote ends of the cover unit 55

and casing. The member 37 is directly secured to the cover unit 2 by means of fasteners 41 which pass through openings in the cover member through similar openings in the ears 46 on said units, engaging nuts 48 behind said ears.

5 Screws 49 inserted through the flange 3 of the cover unit at its remote ends are threadingly engaged with the wall of the casing in the rabbeted portion.

10 When the cover member or unit is removed, the compartmental member 37 is removed with it, so that in replacing or adjusting the lamps, free access is had to all parts of the casing. When the cover member is replaced, the lamps 28 and 29 pass through the openings 41 and the member 37 thus provides one compartment for each lamp, while the lateral extensions 43 and 42, besides dividing the casing generally horizontally, extend the compartments of the lamps 28 and 29 into 20 the connecting shank portion of the arrow heads. Thus, as the lamps are selectively lighted, either arrow head and its adjacent stem portion is illuminated or those areas of the transparency behind the openings 11 and 12.

15 25 The invention having been described, what is claimed as new and useful is:

1. A reflecting unit for direction signals provided with a plurality of parabolic reflecting compartments, said unit and the reflecting compartments being in a unitary structure, and stamped and drawn from sheet metal, whose wall has a definite configuration simulating a pair of direction arrows with one end of each of the arrow stems adjacent the other.

2. In a direction signal, a casing having a closed rear wall and an open front, a removable cover for the open front provided with an opening defining a pair of arrows with one end of each of the arrow stems adjacent the other, a partition unit in said casing and having reflecting parabolic compartments, said unit being in a unitary structure stamped and drawn from sheet metal and whose wall has a definite configuration simulating a pair of direction arrows with one end of each of the arrow stems adjacent the other and conforming to the pair of arrows defined by the opening in the cover, said compartments having clearance openings for lamps. 10

3. In a direction signal, a casing having a closed rear wall and an open front, a removable cover for the open front provided with an opening defining a pair of arrows with one end of each of the arrow stems adjacent the other, a partition unit in said casing and having reflecting parabolic compartments, said unit being in a unitary structure stamped and drawn from sheet metal and whose wall has a definite configuration simulating a pair of direction arrows with one end of each of the arrow stems adjacent the other and conforming to the pair of arrows defined by the opening in the cover, said compartments having clearance openings for lamps, and means adjacent each other near the center of the length of the unit and being integral parts of the wall of the unit and carrying devices to secure the unit to the cover. 20 25 30

JOHN RALPH HAINES.
